UNITED STATES PATENT OFFICE.

ANTON POLLAK, OF PARIS, FRANCE.

CONTACT DEVICE FOR INTERRUPTERS.

1,164,313.

Specification of Letters Patent.

Patented Dec. 14, 1915.

Application filed March 18, 1913. Serial No. 755,094.

To all whom it may concern:

Be it known that I, ANTON POLLAK, a subject of the King of Hungary, residing in Paris, France, have invented certain new and useful Improvements in Contact Devices for Interrupters, of which the following is a specification.

The invention relates to electric interrupters in which the two contacts are arranged one facing the other in the ordinary manner. In this sort of interrupters, which are especially employed in the Wagner hammer, it frequently happens that the contacts very rapidly deteriorate in consequence of the formation of dirt or ridges, which after a certain time resist the passage of the current. This deterioration occurs very rapidly in interrupters of the sort named on account of the high frequency of the interruption spark which passes between the two contacts. If the contacts are of metal, then at that point where the first spark has leaped across the next spark also seeks to pass in consequence of the elevation of temperature produced by the first spark. The result thereof is that the contacts are eaten away at this point. If the contacts, on the other hand, are carbon then there is formed at this point a ridge which gradually increases and finally extends across the space between the two contacts.

For avoiding injurious phenomena of the character above mentioned it has been proposed that interrupters be constructed to impart to one or both contacts, besides the ordinary movement for interrupting the current, a second movement, producing a relative shifting of the contact surfaces and causing friction at such surfaces. It has been proposed for example to arrange the contact on a sheet spring, which on the occasion of shock or other influences causes oscillation of the contacts perpendicularly to the movement of interruption.

The object of the present invention is to assure under all circumstances the most perfect working of this kind of interrupters. In accordance with the invention the contact executing the secondary movement is attached to a system of several springs, whereby the important additional technical effect is obtained, that not only the effect of the vibration itself is increased but that under all circumstances the simultaneous movement of two or several springs assures a strictly parallel displacement, and this with

a single spring (especially if the same, as in the well known devices is slackened against the contact, that is, against the free loaded end) is not the case in consequence of possible breaking or other disturbing movement. In the application of two or several parallel springs the contact executing the secondary movement is assured in its plane of vibration against the other contact however strong be its own vibration. In order to attain, in the most effective manner, the continued change of the contact points from time to time, in accordance with the invention the period of vibration of the displacement movement is chosen longer than that of the interruption movement, in order to surely effect a relative movement of the two points between which the previous interruption took place.

The drawings illustrate the invention in several embodiments by way of examples.

Figures 1, 2 and 3 are side elevations of three different arrangements embodying the invention in simple forms. Fig. 2^a is a plan view of the mechanism shown in Fig. 2. Fig. 4 is a vertical section of an arrangement for producing a rotary movement. Fig. 5 is an elevation of the same. Fig. 6 is a horizontal section of another arrangement for producing a rotary movement, and Fig. 7 an elevation of the same, partly in section.

The construction shown in Fig. 1 is suitable for cases where the interrupter is suspended in such a way that it is exposed to external vibration, for example when it is arranged on a dynamo, a motor, or a power vehicle; or, when the interrupters are closed with a shock sufficient to set in vibration a spring acting on one of the contacts. The contact A has the form of a hammer, which can oscillate about a. The contact B, instead of being perfectly rigid, is carried by two or several parallel flat springs C which stand perpendicular to the contact surface, whereby the contact B is stationary in the direction of movement of the contact A and can vibrate in a direction parallel to its contact face. A weight D is connected with the contact B. If the device consisting of the two contacts is set into vibration, then the contact B will move back and forth parallel to the contact surface, whereby there is produced between the two surfaces the desired displacement and friction. The weight D increases the effect.

If the contact B is itself heavy enough, then the use of a special weight D is superfluous.

The construction illustrated in Figs. 2 and 2^a is also adapted for interrupters which are exposed to external shock. In this arrangement the contact B is fixed. Of the two pivot pins *a* on opposite sides of the contact A, the one which lies behind the surface of the paper is supported in the ordinary manner, whereas the one lying to the front is supported on a yoke *b* which forms one arm of a bell-crank E, which at the end of the other arm carries a weight F, which is held by a spring *f*. The weight F swings under the action of the external shocks and thereby causes the lever E to swing with it which by means of the yoke imparts to the contact A slight displacements in a plane which is parallel to that of the contact surfaces. There will therefore take place between these surfaces a slight friction which is sufficient to attain the end in view.

The arrangement according to Fig. 3, is, in contradistinction to those previously described, employed if the contacts are not exposed to sufficient external vibration. In all the figures the contact A is that which is moved in the interrupting operation and the contact B the one which is at rest. To permit displacement of the contact B (in Fig. 3) in a direction parallel to the contact surfaces, it is supported by two or several leaf springs C which permit vibration in the desired direction. Moreover it is provided with an armature of soft iron G which can be moved by a special electromagnet which is traversed by any variable or intermittent current whatever. In the construction illustrated, however, the electromagnet which produces the displacements of the contact A itself is used to impart the desired blow or movement to the armature G. For this purpose the electromagnet I, causing the change of position of the contact A is provided with a prolongation *i* which acts upon the soft iron armature G to which the contact B is fastened.

In all the above described devices the interrupting mechanism and the lateral displacement mechanism may have different periods of oscillation, and the amplitude of the two movements can be chosen in such manner that it is most favorable for producing the parallel displacement and the friction in the desired manner, the duration of vibration of displacement movement is preferably chosen longer than the movement of interruption, whereby the contact will be surely held in the regulation condition, and the interruption of the current becomes more rapid.

The contact B may also be arranged to produce the parallel displacements through

a rotation or oscillation about its longitudinal axis, this rotation or vibration being produced by means of any desired device. Especially in the case where strong currents are to be constantly interrupted and the amplitude of the back and forth swing is not great, it appears advisable to impart to one of the contacts together with vibrating movement, a constant, even if slow, rotation in order that those points between which the current has just passed and become interrupted shall be thereafter removed from each other locally. In this mode of operation the two contact surfaces remain perfectly smooth and uniform, even in cases of an overload which might produce craters on the surfaces under a strain or overload continued for a comparatively long time in the vibratory devices above described. The vibratory movements above described may be utilized at the same time for imparting to the contact the desired rotation. For this purpose the contact may be connected with a ratchet wheel which engages a stationary pawl and is thereby rotated.

The contact B (Fig. 4) is set into the frame 1 which carries a ratchet wheel 2. The frame 1 has internal longitudinal grooves 4 and 5 which receive similar projections 6 and 7 on the contact B. The pressure spring 3 and the pin 8 determine the position of the contact B in the direction toward and from the interrupter contact A. By means of the set screw 9 the contact B can be set up. The frame 1 is rotatably arranged in the body 10 which is carried by the two springs 11 and 12 (Fig. 5) so that this body 10 on vibrations or influences of the above-described kind oscillates in the direction of the arrow. At each oscillation the ratchet wheel 2 is pushed against the pawl 13, which may consist of a small spring, whereby the ratchet wheel is rotated forward one or more teeth. There arises thereby a progressive rotation of the contact B. The set screw 9 remains stationary while the metal pin 8 lying in the two hollows 14, 15, allows the free swinging of the body 10, and at the same time serves for the conducting of the current. If the contact B is of carbon, then it is provided with a metal cap 16 at the point of engagement with the metal pin 8.

In the construction shown in Figs. 6 and 7 there is effected, in addition to a vibration and a continuous rotation, an automatic setting up of the contact B as it wears away. This device differs from the one described in connection with Figs. 4 and 5, first in the fact that the set screw 9 and metal pin 8 are lacking. The ratchet wheel 2 is held fast in the body 10 by means of the spring 21 which for the purpose of permitting removal of the ratchet wheel is rotatable relatively to

- the frame and contact B. Further, the frame 1 is open at the front and the body 10 is provided with lugs 22, 22 against which the pressure spring 3 presses the contact B.
- 5 Pins 23 serve to carry the contact B with the rotating ratchet wheel. The contact A has in this case an oblong cross-section and a similar contact face, so that the latter is longer than the diameter of the contact B.
- 10 Contact B (the positive pole) at the point of engagement with the contact A is slowly used up. In consequence of the rotation of the contact B all the points of the same pass over the contact face of A gradually, where-
- 15 by in consequence of the pressure of the spring 3 the front surface of the contact B is held automatically and constantly against the lugs 22, 22, so that its working contact surface remains unchanged as regards the
- 20 contact A.

The contact B in both the embodiments illustrated in Figs. 4-7, is perforated in the middle because in the middle portion the effect aimed at by the rotation would not

25 occur.

I claim as my invention:—

1. A contact device for interrupters including a pair of contacts, one of which is movable toward and away from the other, and a system of springs for supporting one of said contacts, said springs being yieldable transversely of the contact movement of said contacts and rigid in the line of such movement whereby a secondary movement of the contacts will be afforded in a direction parallel with the contact surface, and means for rotating one of said contacts relatively to the other.
- 30 2. A contact device for interrupters including a pair of contacts one of which is

movable toward and away from the other, and a spring support for the other adapted to permit vibration thereof in a direction transverse to the movement of the first, and means operated by said transverse movement for producing a rotary movement of the contact member carried by the spring support.

3. A contact device for interrupters including a pair of contacts one of which is movable toward and from the other, a system of springs yieldable transversely of the contact movement of said contacts and rigid in the line of such movement, carrying means mounted on said springs for said other contact, a ratchet wheel connected to the said contact carrying means, and a stationary pawl for engaging the ratchet wheel.

4. A contact device for interrupters including a pair of contacts one of which is movable toward and from the other, a system of springs yieldable transversely of the contact movement of said contacts and rigid in the line of such movement, carrying means mounted on said springs for said other contact, a ratchet wheel connected to the said contact carrying means, and a stationary pawl for engaging the ratchet wheel, said carrier being provided with lugs for positioning the contact face of the contact carried thereby, and a spring for pressing said contact against the lugs.

In witness whereof, I have hereunto signed my name in the presence of two subscribing witnesses.

ANTON POLLAK.
